UNITED STATES PATENT OFFICE.

EGBERT WHITNEY, OF OMAHA, NEBRASKA.

HOISTING-MACHINE.

1,114,832.

Specification of Letters Patent.

Patented Oct. 27, 1914.

Application filed November 22, 1913. Serial No. 802,418.

To all whom it may concern:

Be it known that I, EGBERT WHITNEY, a citizen of the United States, residing in the city of Omaha, county of Douglas, and State 5 of Nebraska, have invented certain new and useful Improvements in Hoisting-Machines, and have described the same in the following specification, illustrated by the accompanying drawings.

10 My invention relates to that class of hoisting machines which are commonly used in pairs suspended by cables at the side of a building in process of construction for the purpose of raising, lowering and supporting 15 a platform for the accommodation of brick-layers and other workmen. A typical machine of this class is the subject of Letters Patent of the United States No. 998,270, which were issued to me July 18, 1911, for 20 improvements in scaffolds.

The principal objects of the invention are these, viz: to simplify the construction, and reduce the number of parts and the cost of manufacture, of machines of this class; to 25 make the machines compact, and to protect their clutch mechanisms from snow, ice, mortar, etc., and from personal interference; to avoid unnecessary friction; to hold the cables approximately straight constantly, and 30 thereby avoid the work that would be involved in bending them around drums; to apply the operative power to the cables with maximum directness, and thereby to raise the given loads with minimum efforts; to 35 facilitate the operative engagement of the machines with the cables and also with the platforms; and in general to increase the efficiency of machines of this class. To accomplish these objects I incorporate in my 40 improved hoisting machine a pair of automatic clutches adapted to engage a suspending cable, means for holding the clutches constantly in vertical alinement and for carrying a load suspended therefrom, means 45 for working the clutches repetitiously toward and from each other in such alinement upon the cable, and means for releasing the clutches severally.

In said drawings, illustrating the best 50 manner in which I have contemplated applying the principles of the invention Figure 1 is a side elevation of a hoisting machine which is constructed of iron and steel in accordance with these principles, and is 55 applied to a suspending wire cable. Fig. 2

is a vertical axial section of a portion of Fig. 1, including the lower clutch. Fig. 3 is a horizontal section on the section line $x-x$ of Fig. 2. Fig. 4 is a like section of the clutch casing on the section line $y-y$ of Fig. 60 2. Fig. 5 is a perspective view of one of the clutch jaws. Fig. 6 is a perspective view of a portion of a pair of the clutch jaws. Fig. 7 is a detail.

In this illustrated and illustrative specimen of my invention, the two alining clutches are mounted respectively in the clutch boxes 1 and 2. Each of these boxes has a vertical peripheral split tubular wall, formed in duplicate wall sections 3 and 4, 70 marginally contacting with each other, a cap 5 fitted over the top of the wall, and an inverted cap 6 fitted to the bottom of the same. These caps hold the contacting wall sections rigidly together, and have each a 75 hole 7 through the middle for the accommodation of the steel wire cable 8, which is suspended from above. By these caps and their terminal perforations 9, the upper clutch box has a rigid engagement, and the 80 lower clutch box a sliding engagement, with the vertical side rods 10, occupying those perforations. The lower clutch box is movable vertically a short distance toward and from the upper clutch box on and between 85 these rods by the split hand lever 11, which works like a pump handle, on a pivot 12 projecting from that box, and is connected by the link 13 with the stop bracket 14 fixed on one of these rods. The clutch in each of 90 these boxes comprises two duplicate vertically disposed semi-tubular jaws 15, mounted on the springs 16, and registering with each other face to face, being held in that 95 position by the transverse guiding arms 17, working in the transverse slots 18 as the jaws approach and recede from each other. Being so held, they are movable vertically in unison between the anti-friction rollers 19, on the rivets 20 extending horizontally 100 through the box. These jaws have the internal riblike teeth 21 arranged in relatively staggered positions in the two jaws respectively, to bite the cable; and external wedge-shaped projections 22 on the back of each 105 jaw, to engage the rollers 19 and thereby to produce and to release the bite as the clutch rises and falls in the box. The key 24, is a removable pin longitudinally slidable by hand in the vertical hole 25 through the top 110

of either cap 5 alternatively, and adapted by downward pressure to depress and thereby release the described clutches.

The transverse and removable cross plate 5 23, which is perforated to accommodate the cable 8 connects the side rods 10 at the bottom, and is intended to support the platform.

When undisturbed by manipulation, both 10 clutches of the loaded machine grip the suspending cable; the lower clutch being actuated by the clutch springs, which force the wedging jaws upward and together between the rollers 19; and the upper clutch 15 being additionally actuated by the downward pull of the platform or other load, communicated to those rollers through the side rods 10 and the upper clutch box, and forcing the jaws together. To raise the 20 load, a workman first lifts the free end of the lever, thereby releasing and raising the lower clutch box, and then forces down the lever, thereby bringing the lower clutch into action and releasing and lifting the 25 upper clutch from which the load is suspended. By thus raising and lowering the lever repetitiously, like a pump handle, he causes the machine to climb the cable with an inch worm movement, so to speak, and 30 raises the platform to any desired level step by step. To lower the load, both clutches gripping as above described, the operator first releases the upper clutch with the key 24, then lets down the upper clutch 35 box and the dependent load by raising the lever, then with the same key, transferred to the lower clutch box, while the upper clutch automatically grips the cable, he releases the lower clutch and then lowers the 40 lower clutch box in the same manner, thereby placing the machine in posture for raising or lowering again in the same manner.

Constructed and operating as described, the machine accomplishes the above stated 45 object of my invention in all its branches.

I claim:

1. A hoisting machine of the specified class, comprising two automatic clutches adapted to grip alternatively a suspending 50 cable, means for raising and lowering the clutches independently on the cable, and a suspended frame, upheld by the clutches alternatively and provided with means for holding both clutches in vertical alinement.
- 55 2. A hoisting machine of the specified class, comprising two automatic clutches adapted to engage a suspending cable, means for holding the clutches constantly in ver-

tical alinement and for carrying a load suspended therefrom, means for moving the 60 clutches toward and from each other in such alinement, and means for releasing the clutches severally.

3. A hoisting machine of the specified class comprising two automatic clutches, means 65 for holding the clutches in vertical alinement and for carrying a suspended load, means for moving the clutches toward and from each other in such alinement, and means for releasing the clutches severally; 70 each clutch having two co-acting, spring-mounted, vertical wedge jaws between anti-friction rollers, and being adapted to grip automatically a suspending cable and to be released from that cable. 75

4. A hoisting machine of the specified class, comprising two clutches adapted to grip a cable automatically, two clutch boxes holding the clutches respectively, two vertical rods having a rigid connection with one 80 of the clutch boxes and a sliding engagement with the other, and holding the clutch boxes and contained clutches constantly in vertical alinement at a changeable distance apart, a cross connection between the rods for the 85 support of the load, means for sliding one of the clutch boxes toward and from the other on the vertical rods, and means for releasing the clutches severally.

5. A hoisting machine of the specified 90 class, comprising two automatic clutches adapted to grip a suspending cable, means for holding the clutches constantly in vertical alinement and for carrying the load suspended therefrom, means for releasing 95 the clutches severally, and a link and lever connection between the clutches for moving them toward and from each other.

6. A hoisting machine of the specified class, comprising two automatic clutches 100 adapted to grip a suspending cable, separate boxes inclosing the clutches respectively, means for holding the clutch boxes in vertical alinement at varying distances apart and for carrying a load, means for 105 reciprocating the clutch boxes, and a key slideable in a hole in each box for releasing the contained clutch.

In testimony whereof I subscribe my name hereto in the presence of two witnesses.

EGBERT WHITNEY.
